T. O. AKED.
SPINNING MACHINE SPINDLE.
APPLICATION FILED DEC. 30, 1915.

1,240,803.

Patented Sept. 25, 1917.

UNITED STATES PATENT OFFICE.

THOMAS OSWALD AKED, OF ST. THOMAS, ONTARIO, CANADA.

SPINNING-MACHINE SPINDLE.

1,240,803.

Specification of Letters Patent. Patented Sept. 25, 1917.

Application filed December 30, 1915. Serial No. 69,416.

To all whom it may concern:

Be it known that I, THOMAS OSWALD AKED, a subject of the King of Great Britain and resident of St. Thomas, province of Ontario, in the Dominion of Canada, have invented a certain new and useful Improvement in Spinning-Machine Spindles, of which the following description having reference to the accompanying sheet of drawings is a specification.

My invention relates to spindles for the class of spinning, twisting and like machines wherein flyers are used and to that type of spindle which does not revolve with a flyer, and which is therefore known and usually styled a "dead spindle." As is well known in this type of spindle considerable difficulty is experienced in providing means for effecting the efficient lubrication of the parts rotated upon or about them. My present invention consists in the formation or construction of certain of the parts hereinafter described whereby the result desired is attained.

In the accompanying drawings:—

Figure 1 is a sectional elevation (showing the end view of the lifter rail *c*) with a spindle and parts made in accordance with my invention and a bobbin mounted thereon.

Fig. 2 is a plan of the parts shown by Fig. 1.

Fig. 3 is a sectional plan on line A—B of parts shown by Fig. 1.

Fig. 4 is a similar view to Fig. 1 but illustrates a modification hereinafter described.

The dead spindle 2 is fixed upon the lifter rail *c* and upon said spindle I mount a tube 3 which is free to revolve thereon in a manner well known. This tube 3 has its upper end plugged or filled with a bearing or plug 4 from which extends a pin or projecting rotary spindle 5 downwardly from the plug into the spindle 2. To receive this spindle 5 I form an axial opening 2^a in the upper end of the dead spindle 2, so that the lower conical end of the spindle 5 may take therein and rotate freely thereon. The opening 2^a is made sufficiently long to take an appropriate length of the rotary spindle 5 to afford stability to the tube 3 as the same may be pressed in a lateral direction. At the lower end of the tube 3 an appropriate split ring or like device 6 is inserted so that it may take into an outer groove 2^b formed in the dead spindle 2, thus securing the tube 3 upon the dead spindle in order that

when the operative removes the bobbin 7 therefrom said tube 3 is not detached from the spindle 2. In cases where the formation of a groove 2^b in the dead spindle weakens the latter more than is desired, then (as shown by Fig. 4) to prevent the tube 3 from being readily removed from the dead spindle I turn the outer end 3^a of said tube 3 in a radial direction so as to form a radial flange 65 thereon and over the tube 3 I place a plate 8 having a recess 8^a to receive the radial flange 3^a of the tube 3 which will prevent the removal thereof as will be understood. The upper surface of this plate 8 is similar to the upper surface of the washer 9 shown by Fig. 1, both of which are to receive the drag washers 10 for the purposes well known. By the employment of the plate 8 the groove 2^b in the spindle 2 is not required, hence said 75 spindle 2 may retain its full strength throughout its length. Taking over the tube 3 is the bobbin 7 which is arranged to rest upon the drag washers 10 in manner well known, thus as said bobbin is rotated upon 80 said drag washers when it contacts with the tube 3 said tube 3 will also freely rotate about the dead spindle 2. As shown by Figs. 1 and 4, the upper end of the bobbin is substantially flush with the upper end 85 of the plug 4, the arrangement being such as to facilitate the feeding of the lubricant into the cavity 4^a.

In order to facilitate the lubricating of the spindle 5 I have holes or ducts 11 made 90 through the plug 4 to lead into the conical opening 2^a at the upper end of the spindle 2, while an appropriate cavity 4^a is formed in the upper end of the said plug 4, into which the lubricant may be poured so that the same 95 may travel down the ducts 11 into the position at the base of the spindle 5 as will be understood.

Such being the nature and object of my said invention, what I claim is:—

1. In spinning machines, in combination, a dead spindle having an axial opening, a tube fitting loosely thereover, a plug fitting within said tube and having a cavity at its upper end and ducts leading through said 105 plug from said cavity into proximity to the upper end of said spindle, and a pin extending from said plug within said axial opening.

2. In spinning machines, in combination, a dead spindle having an axial opening, a tube taking loosely thereover, a plug fitting

- within the end of said tube, and having a cavity at its upper end and ducts leading through said plug from said cavity into proximity to the upper end of said spindle, 5 an extension from said plug leading within said axial opening, a bearing at the lower end of said extension, said dead spindle having a groove formed in its inner end portion, and a split ring fitting within said groove.
- 10 3. In spinning machines, in combination, a dead spindle having an axial opening, a tube fitting thereover, a plug fitting within said tube with its upper surface flush with the end of said tube, a rotary spindle extending from said plug, the dead spindle being provided with an axial opening for the reception of said rotary spindle, and with a conical opening at its upper end, said plug being provided with a cavity formed in its 15 upper end and with ducts leading from said

cavity, and means for preventing the ready detachment of said tube.

4. In spinning machines, in combination, a dead spindle having an axial opening formed therein, a tube fitting loosely over said spindle, a plug fixed in said tube, a pin projecting from said plug and extending within said axial opening to act as a support, said plug being provided with a cavity and with ducts leading from said cavity, means for preventing the ready removal of said tube, a bobbin fitting over said tube with its upper end arranged to leave the cavity in the plug free to facilitate the feeding of lubricant, and a support for said dead 35 spindle.

THOMAS OSWALD AKED.
